US0D1104960S

(12) **United States Design Patent** (10) **Patent No.:** **US D1,104,960 S**
Chen (45) **Date of Patent:** **** Dec. 9, 2025**

(54) **PORTABLE CHARGER**

(71) Applicant: **SHENZHEN ENPASSION TECHNOLOGY LTD.**, Guangdong (CN)

(72) Inventor: **Xu Chen**, Guangdong (CN)

(73) Assignee: **SHENZHEN ENPASSION TECHNOLOGY LTD.**, Shenzhen (CN)

(**) Term: **15 Years**

(21) Appl. No.: **29/990,279**

(22) Filed: **Feb. 20, 2025**

(30) **Foreign Application Priority Data**

Sep. 6, 2024 (CN) 202430570466.X

(51) **LOC (15) Cl.** **13-02**

(52) **U.S. Cl.**

USPC **D13/107**; D13/103

(57) **CLAIM**

The ornamental design for a portable charger as shown and described.

DESCRIPTION

FIG. 1 is a perspective view of a portable charger showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the portable charger where the portable charger is in a configuration of use; and,

FIG. 10 is an enlarged view of portion 10 shown in FIG. 1. The dash-dash broken lines in the drawings depict portions of the portable charger that form no part of the claimed design. The dot-dash broken lines in FIGS. 1 and 10 represent a boundary of the enlarged portion and form no part of the claimed design.

1 Claim, 10 Drawing Sheets
